UNITED STATES PATENT OFFICE.

JOSEPH B. LEGATE, OF JERSEYVILLE, ILLINOIS.

THILL-COUPING.

SPECIFICATION forming part of Letters Patent No. 561,799, dated June 9, 1896.

Application filed November 4, 1895. Serial No. 567,842. (No model.)

To all whom it may concern:

Be it known that I, JOSEPH B. LEGATE, of Jerseyville, in the county of Jersey and State of Illinois, have invented a new and Improved 5 Thill-Coupling; and I do hereby declare that the following is a full and exact description of the same, reference being had to the accompanying drawings and to the letters of reference marked thereon.

10 My invention relates to improvements in thill-couplings, my object being to provide a coupling of very simple construction, devoid of small detachable parts liable to fall out of position accidentally and be lost or requiring to be removed in order to take the shafts or draft-pole from the vehicle.

With these ends in view my device consists in certain details of construction and combinations of parts fully explained in the following specification, and illustrated in the accompanying drawings, in which—

20 Figure 1 is a side elevation of the device, partly shown in section. Fig. 2 is a top view of the same, and Fig. 3 is a bottom view 25 thereof.

Referring to the drawings, A represents the axle of the vehicle, and B a clip of the ordinary form, with which is connected a coupling-box C, the latter adapted to receive the butt-end 30 D of the thill-iron, which is provided with two dowels d, for the reception of which, when the shafts are turned down into position for use, two slightly-elongated sockets are provided in the top of the coupling-box C, as 35 shown in Figs. 1 and 2. S represents a spring adapted to serve the double purpose, by means of the nuts and screws r, of securing 40 the clip B in position upon the axle and of sustaining the thill-iron D in the required position within the coupling-box C.

It will be noticed that the sockets for the reception of the dowels d are slightly elongated toward the top, so as to prevent the latter binding in their sockets when the forward ends of the shafts are lowered to the

ground or raised slightly above their normal position; also that the rear end of the thill-iron is adapted to butt against the shoulder a, (see Figs. 1 and 2,) so that in backing the vehicle the dowels d are relieved of all strain. 50

Though the spring S is sufficiently elastic to allow the forward ends of the shafts or draft-pole to vibrate freely, it is made strong enough to hold the thill-iron firmly against the top of the coupling-box C. 55

To remove the shafts from the axle, it is only necessary to turn them up to about a vertical position, as indicated by the arrow 1, Fig. 1, so as to withdraw the dowels d from their sockets, and then lift the shafts vertically, as indicated by arrow 2. Their replacement is effected by a similar operation in reverse order. 60

Having fully described my invention, what I claim, and desire to secure by Letters Patent, is—

A thill-coupling comprising an axle-clip provided with a forward-projecting box for the reception of the rear end of the thill-iron, a thill-iron having a flat head of rectangular 70 form provided with dowels adapted, when the thill is turned down into position for use, to occupy sockets provided for their reception in the top of the box connected with the axle-clip, a spring secured, by means of the clip-bolts, to the under side of the axle so as to retain the coupling in position thereon, the free end of said spring adapted to impinge upon the under side of the thill-iron so as to hold the latter securely in place in the coupling-box; all of said parts constructed, combined, and adapted to operate substantially 75 as and for the purpose set forth. 80

In testimony that I claim the foregoing I have hereunto set my hand this 24th day of October, 1895. 85

JOSEPH B. LEGATE.
